UNITED STATES PATENT OFFICE.

JOHAN VIKTOR BLOMQUIST AND KARL FREDRIK WESSBLAD, OF STOCKHOLM,
SWEDEN.

SAFETY GOVERNOR FOR STEAM GENERATORS WITH ROTARY LAYERS OF WATER.

Application filed May 19, 1924. Serial No. 714,488.

To all whom it may concern:

Be it known that we, JOHAN VIKTOR BLOMQUIST and KARL FREDRIK WESSBLAD, both citizens of Sweden, and residing at 5 Stockholm, Sweden, have invented certain new and useful Improvements in Safety Governors for Steam Generators with Rotary Layers of Water, of which the following is a specification.

10 The present invention relates to safety governors for steam generators with rotary layers of water such as described in our co-pending application, Serial Number 621,391, filed Feb. 26, 1923.

15 In steam generators of the type in which the generation of steam takes place in rotary tubular elements or in fixed tubular elements with a rotary layer of water or other liquid the safety of operation is dependent 20 on the rotation of the layer of liquid so as to cause it to entirely cover the inner cylindrical surfaces of the tubular elements. If, for any reason, such rotation ceases, the liquid will fall down and collect at the lower parts 25 of the tubular elements. Consequently, the upper parts of the tubular elements will become filled with steam, and thus the destruction of the tubular elements is threatened on account of the reduced transfer of heat.

30 The present invention relates to a device which reduces the danger of explosion upon cessation of this rotation by automatically opening a valve communicating with the steam space of the generator, as for instance, 35 the safety valve of the generator, and in some cases damping the fire, for instance by stopping a feeding device for the fuel supply and a forced draught blower.

The invention is illustrated, by way of example, in the accompanying drawings wherein;

Fig. 1 shows diagrammatically a boiler plant;

Fig. 2 is a sectional elevation, parts being shown in elevation, of the governor system.

In the drawings, a centrifugal governor 1, is driven by the same driving member 1', as the rotary layer of liquid in boiler element 1'' by means of gearing or the like 2', and 50 the power transmitting means 2'', and, consequently, is brought to a standstill, as soon as the rotation of the layer of liquid ceases for any reason. The centrifugal governor 1 actuates a slide valve 3 by connecting means 55 2. During the rotation of the centrifugal

governor a cylinder 4, connected to casing 3' of valve 3, is brought into communication with the atmosphere through pipe 5, and slide valve 3. When the governor 1 comes to a standstill, however, the cylinder 4 is 60 connected with steam pressure through a pipe 6 leading to the steam space of the generator. During rotation of governor 1, the piston 7 is pressed against the bottom of the cylinder 4 by means of a spring 8, while 65 said piston, as soon as the rotation ceases, is moved from said bottom by the applied steam pressure through pipe 6. This movement of the piston 7 upon cessation of the rotation of governor 1, is utilized for turning a crank 9, 11 on its pivot 10 for the purpose of easing the safety valve 12 and opening the contacts 13 for an electric motor or 70 motors 14, operating a fuel feeding mechanism 15 and blower 16.

75 The device for the opening of the safety valve and the damping of the fire may of course be varied in different ways. The characteristic feature of the invention is that a centrifugal governor driven from the same driving member as the rotary layer of liquid is adapted to open a valve communicating with the steam space of the generator, as soon as the governor ceases to rotate and in some cases also to damp the fire, as for 80 instance by stopping the fuel feed mechanism and the forced draught blower.

Having thus described our invention what we claim and desire to secure by Letters Patent is:—

90 1. A steam generator, comprising a tubular element, means for centrifugally positioning a layer of liquid in the element, a rotary controlling member driven at a speed proportional to the speed of rotation of the layer of liquid, a valve communicating with the steam space of the generator, and means operatively connecting said controlling member with said valve and acting to hold said valve closed while the controlling 95 member rotates, and to hold said valve open while the controlling member does not rotate.

2. A steam generator, comprising, a tubular element, means for centrifugally positioning a layer of liquid in the element, a 100 centrifugal governor driven at a speed proportional to the speed of rotation of the layer of liquid, a fuel feed mechanism, and means operatively connecting said centrifugal governor with said fuel feed mech- 110

anism, said connecting means operating to stop said fuel feed mechanism upon the cessation of rotation of said centrifugal governor.

- 5 3. A steam generator, comprising, a tubular element, means for centrifugally positioning a layer of liquid in the element, a centrifugal governor driven at a speed proportional to the speed of rotation of the 50
10 layer of liquid, a forced draught blower, and means operatively connecting said centrifugal governor with said forced draught blower, said connecting means operating to 55 stop said forced draught blower upon cessation of rotation of said centrifugal governor.

- 15 4. A steam generator, comprising, a tubular element, means for centrifugally positioning a layer of liquid in the element, a centrifugal governor driven at a speed proportional to the speed of rotation of the 60
20 layer of liquid, a valve communicating with the steam space of the steam generator, a fuel feed mechanism, and means operatively connecting said centrifugal governor with both the valve and the fuel feed mechanism, said means operating to open said valve and 65
25 to stop said fuel feed mechanism upon the cessation of rotation of said centrifugal governor.

- 30 5. A steam generator, comprising, a tubular element, means for centrifugally positioning a layer of liquid in the element, a centrifugal governor driven at a speed proportional to the speed of rotation of the 70
35 layer of liquid, a valve communicating with the steam space of the steam generator, a forced draught blower, and means operatively connecting said centrifugal governor with both the valve and the forced draught blower, said means operating to open said valve and 75
40 to stop said forced draught blower upon cessation of rotation of said centrifugal governor.

- 45 6. A steam generator, comprising, a tubular element, means for centrifugally positioning a layer of liquid in the element, a centrifugal governor driven at a speed pro-

portional to the speed of rotation of the layer of liquid, a valve communicating with the steam space of the steam generator, a fuel feed mechanism, a forced draught blower, and means operatively connecting said centrifugal governor with the valve, the fuel feed mechanism, and the forced draught blower, said connecting means operating to open the valve, and to stop both the fuel feed mechanism and the forced draught blower, upon cessation of rotation of said centrifugal governor.

7. A steam generator, comprising, a tubular element, means for centrifugally positioning a layer of liquid in the element, a centrifugal governor driven at a speed proportional to the speed of rotation of the 80
85 layer of liquid, a slide valve mechanically connected to the centrifugal governor, a cylinder, said slide valve being arranged, when reciprocated, to connect the cylinder either with a steam supply or with atmosphere, said cylinder being provided with a spring actuated piston having a piston rod, a valve communicating with the steam space of the steam generator, a fuel feed mechanism, a forced draught blower, and controlling means operatively connecting said piston rod with the valve, the fuel feed mechanism, and the forced draught blower, said slide valve operating to bring said cylinder into communication with the steam supply upon cessation of rotation of the 85
90 centrifugal governor, whereby said controlling means is actuated, the valve connected to the controlling means is opened, and the fuel feed mechanism and the forced draught blower are both stopped.

In testimony whereof, we have signed our names to this specification, in the presence of two subscribing witnesses.

JOHAN VIKTOR BLOMQUIST.
KARL FREDRIK WESSBLAD.
